DISINTEGRATING AND STABILIZING APPARATUS

Lewis M. McBride, Edgewood Arsenal, Md.

Application July 6, 1939, Serial No. 283,031

8 Claims. (Cl. 83—9)

(Granted under the act of March 3, 1883, as amended April 30, 1928; 370 O. G. 757)

The invention described herein may be manufactured and used by or for the Government for governmental purposes, without the payment to me of any royalty thereon.

This invention relates to the disintegration of solid substances, the dispersion and stabilization of the finely ground particles to prevent coagulation, and the collection of the stabilized fine particles.

One object of the invention is to provide an impact mill wherein normally solid substances are ground to an impalpable powder which is continuously removed from the impact zone to prevent cushioning of the impact elements.

Another object is to provide an impact mill of the above type in combination with means whereby the finely ground particles are dispersed and stabilized such that the material will remain indefinitely as a fine dust.

Another object is to provide an impact mill and associated mechanism which is relatively economical to construct and simple to operate and which may be continuously used to produce stabilized fine particles of substances which have a tendency to cohere and coalesce.

Another object is to provide a means of producing a finely divided solid material consisting of two or more components of active material in a stabilized condition, such that the individual particles of one component will not recombine or cohere with other particles of the same component and, also such that the particles of different components will not combine with or adhere to each other.

In all processes of mechanical disintegration, the different particles into which the substance is divided have to be torn apart against the force of cohesion. Disintegration may be accomplished by shearing and tensile stresses gradually applied, as in attrition mills, or by a crushing pressure applied gradually by means of rolls, or by sudden blows, as in impact machines of the disintegrator type.

The efficiency with which the applied stress can act will depend upon the rigidity with which it is received by the pieces of substance that are to be broken. As the particles gradually become smaller, they form a loose dust that yields more and more to the applied stress, so that the crushing effect is increasingly diminished. There comes a point, therefore, in all crushing operations at which the accumulated debris is fine enough to accommodate itself to the applied stress without the individual particles actually being stressed beyond their elastic limit. The

rigidity of the mass is then too low for further crushing stresses to produce any effect.

To disintegrate the material further, it is evident that the finest particles of the debris which are cushioning the larger remaining particles against the crushing effect of the process must be removed in order to allow the disintegration action to continue. To separate these finest particles from the coarse and remove them from the crushing process and continue the disintegration of the remainder is one of the principal features of this invention.

The manner in which this is done contributes directly to another principal feature of the invention by disassociating any aggregates and dispersing the fine particles and isolating them in air or other gas whereby they are permitted and caused to adsorb upon their surfaces molecules or films of air or gas; also, by virtue of the process, fine particles of a particular type of material, according to its chemical nature, acquire an electrical charge of a definite sign, the adsorbed air or gas and/or the effect of the electrical charges produce a stabilized particle preventing recombining or the formation of aggregates of the individual particles. Further, the method used to accomplish these results is also used to provide a convenient means of retaining and collecting the processed material for use.

This application is a continuation-in-part of my prior application now Patent No. 2,165,287 granted July 11, 1939, filed April 12, 1935, for Method and apparatus for disintegration, dispersion, stabilization and collection of solid materials.

Referring to the drawings

Fig. 1 is a plan of the mill and stabilization and collection mechanism.

Fig. 2 is an elevation.

Fig. 3 is a broken section of the interior of the mill.

Fig. 4 is a section on line 4—4 of Fig. 3.

Fig. 5 is a central section of the complete mill.

Fig. 6 is a broken section of the mill showing the feed mechanism and hopper.

Fig. 7 is an end view of Fig. 6.

Referring to the drawings, and more especially to Figs. 1 and 2, the system comprises a primary disintegrator or mill 1 more particularly as shown in Figs. 3, 4 and 5. The finely pulverized material passes from mill 1 through pipe 2 to secondary disintegrator 3 which comprises an exhauster and blower driven by motor 4. The pulverized material is blown by blower 3 through

a stabilization and dispersion tube 5 enclosed within an outer tube 6. Cooling liquid such as water is circulated between tubes 5 and 6, the water entering by pipe 7 and leaving at pipe 8.

Tube 5 discharges the dust particles into a centrifugal separator 9, to the top of which is connected tube 11 to carry the fine particles to a dust settler and collector 12. The walls of the dust chamber 12 permit the escape of discharged and spent air but will retain the fine dust particles, the area of the walls being proportioned to the volume of air delivered by blower 3, so that the velocity of the air through the filter will be low.

The spent air passes through flue 13 to a final dust arrester 14 and thence to exhaust pipe 15. Arrester 14 also includes a fine fabric filter to extract the finest particles which may have passed collector 12. It will be understood that separator 9, collector 12 and arrester 14 include means to remove the collected dust therefrom.

Referring now to Figs. 3, 4 and 5, the mill 1 comprises a rotary drum 16 mounted for rotation on a stationary hollow shaft 17. Within the drum are a plurality of rollers 18 which fall upon the material being ground as illustrated in Fig. 4 to crush and disintegrate the material. Hollow shaft 17 has a plurality of upright hollow tubes 19 connected to the shaft adjacent the end opposite the material feed end of the mill. Central shaft 17 has a plug 21 about midway thereof and another upright hollow shaft 22 thereon.

Central shaft 17 has two slots therein, one such slot 23 being within the drum 16 and opening downwardly, the other slot 24 being outside the drum and facing upwardly. These slots are for feeding the material to be ground into the mill.

Referring to Figs. 6 and 7, a feed hopper 25 is secured over slot 24 and is provided with a valve controlled by handle 26 whereby material may be fed through slot 24 into hollow shaft 17. A hollow plunger 27 is telescoped into shaft 17 and is closed at its inner end by a plug 28 and has a handle 29 on its outer end. Tube 27 is provided with a slot 31 into which a stop pin 32 on tube 17 projects. Slot 31 has a short section at right angles, which extends about 90° around tube 27.

Material is fed into the mill by rotating inner tube 27 until stop pin 32 aligns with longitudinal slot 31, then pulling tube 27 outwardly until pin 32 is at the end of the slot. Valve handle 26 is then turned to allow a charge of material to fall into hollow shaft 17, after which valve handle 26 is turned to close the feed valve. Then inner tube 27 is telescoped back into shaft 17 and the charge of material is forced into the mill by plug 28 and falls through slot 23 in shaft 17.

One principal feature of this invention is the means whereby air or other gaseous medium enters the mill to continuously remove only the finest dust particles as they are ground. This air enters the mill partly through hollow shaft 17 and partly through the periphery of the drum. The tube 27 has an opening 33 (Fig. 6) which is longitudinally aligned with vertical tube 22 when the telescoping tube 27 is pushed into place. When tube 27 is rotated 90° from the position shown in Fig. 6, this opening 33 coincides with tube 22, so that air enters the mill as shown in Fig. 3.

As seen in Figs. 3, 4 and 5, the drum 16 has three openings 34 which are spaced 120° apart around the drum and are equally spaced longi-

tudinally thereof as shown. Air is drawn into these openings as seen in Figs. 3 and 4. It will be noted that some of the air drawn into the drum passes through the material being disintegrated, whereby the finest ground particles are carried upwardly and out of the mass of material, thus avoiding cushioning of the rollers. The uniform angular spacing of openings 34 and the manner in which they lead one another successively from rear to front tends to agitate the material under and between the entire surface of the rollers and to carry the fines from the rear to the front and out of the mill.

The incoming air prevents the material from falling out of the mill through openings 34. Removable plugs 35 as shown in Fig. 4 are provided for openings 34, and these plugs are used when the mill is started up before there has been any grinding.

The operation of the apparatus is as follows. A charge of material is fed into the mill by withdrawing feed tube 27, operating feed handle 26 to allow a charge to enter tube 11, then returning tube 27. Plugs 35 are placed in openings 34 and the primary disintegrator or mill 1 is started. The drum 17 rotates relatively slowly, in one practical installation at 78 R.P.M. Rollers 18 are carried up the side of drum 17 and fall as shown in Fig. 4, whereby the material is crushed by impact and sliding and rolling movements of the rollers.

After some of the coarse material has been ground, the mill is stopped and plugs 35 removed. Secondary disintegrator or blower 3 is then started, tube 27 being rotated to align opening 33 with stationary tube 22. The mill is started and air is drawn into the same through telescoping tube 27, opening 33 and tube 22, and also through openings 34 in the mill wall. This air passes upwardly and is drawn out of the disintegrator through stationary tubes 19 and central shaft 17. It will be seen from Figs. 3 and 4 that the air is withdrawn from an area spaced substantially above the disintegrating area, whereby only the finest floating particles are withdrawn.

The quantity of air withdrawn is quite large, so that each dust particle may be and is quickly surrounded with an attached film of air. These suspended particles pass through secondary disintegrator 3 to thereby further break up any possible aggregates, then pass through stabilization and dispersion tube 5 at high velocity which is being cooled by water circulating through tube 6. This cooling of the particles while passing through the stabilization and dispersion tubes in a blast of air at high velocity tends to increase their ability to adsorb films of air or gas and stabilize them and assists in preventing any agglomeration thereof.

The stabilized fines then pass into separator 9 wherein any larger particles settle out, thence to collector 12 and arrester 14, the air being exhausted at 15. Additional charges of material may be readily added, as previously described.

Although not limited thereto, this invention has been successfully used to disintegrate and stabilize chloracetophenone, commonly called tear gas, and diphenylaminechlorarsine, commonly known as sickening gas. The compounds are normally solid and cannot therefore be readily dispersed into the air to form incapacitating clouds. Such dispersion has heretofore been accomplished either by dissolving the compounds in a volatile solvent and spraying the solvent

into the atmosphere, or by mixing with gun powder and causing burning thereof. Both these methods are relatively inefficient. However, when these compounds are disintegrated and stabilized in accordance with this invention, the very finest dust particles are obtained and such particles are so stabilized that they will not subsequently cohere or coagulate in storage. Therefore, these compounds may be dispersed directly as floating dusts, such as by means of a simple dusting apparatus, or by simple grenade described and claimed in my patent application for "Grenade" filed Dec. 2, 1938, Serial Number 243,526.

It will be understood that this invention is not limited to the specific details of construction shown herein by way of illustration, since various changes may be made therein by those skilled in the art without departing from the spirit of the invention nor exceeding the scope of the appended claims.

I claim:

1. An impact mill for disintegrating normally solid material comprising a hollow shaft, a rotatable drum mounted on said shaft, a plurality of impact rollers within said drum, means for continually drawing air at high velocity into one end of said hollow shaft and across the upper portion of said drum and out the other end of said shaft, and means for selectively admitting air through the material and around said rollers and out of said hollow shaft.

2. Apparatus for disintegrating and stabilizing normally solid chemical warfare agents comprising an impact roller mill, a hollow shaft upon which said mill rotates, means for admitting air to one end of said hollow shaft and means for withdrawing air from the other end of said shaft, a plurality of upright pipes connected to said shaft and terminating adjacent the upper portion of said mill, whereby air is drawn into said shaft and across the upper portion of said mill to withdraw only the fine dust particles, a cooling chamber connected to the discharge end of said shaft through which the particles pass while suspended in air, the particles being stabilized by an adhering film of air, and means to collect the stabilized particles.

3. The invention as defined in claim 2 wherein the cooling chamber comprises a relatively long conduit through which the particles pass, said conduit being surrounded by a jacket through which a cooling medium is circulated.

4. An apparatus for disintegrating normally solid material comprising a hollow shaft, a rotatable drum with grinding elements therein mounted on said shaft, means for continually drawing air at high velocity into one end of said hollow shaft, across the upper portion of said drum, and out the other end of said shaft, a single manipulative means at the first mentioned end of said shaft for controlling the admission of the material and air, selectively, through said one end of said shaft, and means providing in the periphery of said drum for selectively admitting air through the material and around the grinding elements and out said other end of the hollow shaft.

5. An apparatus for disintegrating and stabilizing normally solid material comprising a hollow shaft, a rotatable drum with grinding elements therein mounted on said shaft, means for continually drawing air at high velocity into one end of said hollow shaft, across the upper portion of said drum, and out the other end of said shaft, means for selectively admitting air through the material and around the grinding elements and out said other end of the hollow shaft, and means connected with said other end of the hollow shaft receiving air and dust particles emitted from said shaft and subjecting the emitted air and suspended particles to a cooling medium for stabilizing said particles with an adhering film of air.

6. An apparatus for producing chloracetophenone and diphenylamine in stabilized powdered form comprising a hollow shaft, a rotatable drum with grinding elements therein mounted on said shaft, means for continually drawing air at high velocity into one end of said hollow shaft across the upper portion of said drum, and out the other end of said shaft, means for selectively admitting air through the material and around the grinding elements and out said other end of the hollow shaft, and a stabilization tube connected with said other end of said shaft and through which the extracted air and suspended particles pass, said tube being surrounded by a jacket through which a cooling medium circulates.

7. An apparatus for disintegrating and stabilizing normally solid material comprising a rotary impact mill provided at one end with an axially positioned single manipulative means for controlling the admission of the material and air, selectively, into the mill, means for continually drawing air at high velocity into the mill through said single manipulative means, across the mill through an area substantially removed from the grinding area thereof, and out through the other end of the mill, means for selectively admitting air through the material and around the impact elements in the mill and out said other end of the mill, a cooling chamber connected with said other end of the mill and through which the air and suspended particles of the material exhausting from the mill pass for stabilizing said particles with an adhering film of air, and a collector for the stabilized particles connected with said cooling chamber.

8. The method of disintegrating and stabilizing a normally solid irritant chemical agent which normally cakes during storage, which comprises disintegrating the agent to fine dust particles, continuously extracting only the finest dust particles, suspending and transporting the extracted dust particles in a moving stream of air, subjecting the extracted dust particles while in suspension and transit to the action of a cooling medium for stabilizing the particles against coalescence, and collecting the fine dust particles thus stabilized.
